United States Patent Office

Des. 177,292
Patented Mar. 27, 1956

177,292

DRESS

Mamie Verrand, New York, N. Y.

Application August 30, 1955, Serial No. 37,713

Term of patent 7 years

(Cl. D3—26)

Fig. 1 is a front view of a dress showing my new design, and

Fig. 2 is a rear view thereof.

I claim:

The ornamental design for a dress, substantially as shown.
